UNITED STATES PATENT OFFICE.

AMMIEL F. DECKER, OF PELHAM, NEW YORK.

PADDING FOR IRONING ROLLS.

Application filed December 28, 1922. Serial No. 609,543.

To all whom it may concern:

Be it known that I, AMMIEL F. DECKER, a citizen of the United States, residing at Pelham, in the county of Westchester and State 5 of New York, have invented certain new and useful Improvements in Padding for Ironing Rolls, of which the following is a specification.

This invention relates to padding for covering the rolls of ironing machines; and its object, stated briefly, is to provide an improved built-up article or material of the above nature which is constructed in such a way that any size of roll can be easily and 10 quickly padded, while at the same time avoiding the necessity of gluing the padding directly to the bare metal surface of the roll, as has heretofore been done.

According to my invention, I construct 20 the padding of relatively small sections or blocks of cork, compressed wood pulp, wool felt, cotton felt, linoleum, or other suitable material of like character; and of any desired shape or size; and I so connect these 25 blocks together as to enable the composite structure to fit conformably against the surface of the roll.

The fastening means or devices employed for this purpose may be of different characters. For example, I may mount the blocks 30 on, and secure them to, a backing sheet of metal or metallic or other fabric. Again, I may secure the blocks to a metal sheet by means of staples, the ends of which fit in 35 grooves in the blocks, or by means of bolts. I may also form the metal backing sheet with transverse ribs disposed in spaced, parallel relation; and in that instance, I 40 cut away the blocks along their inner longitudinal edges so as to provide seats or recesses wherein the ribs fit, so that the upper faces of these seats or recesses rest upon the ribs, the blocks themselves being faced or lined along the seats or recesses as well as 45 along their inner surfaces with metal wearing strips or plates or left plain, as may be preferred.

Whatever the method employed, it is apparent that the contiguous, longitudinal 50 rows of blocks will conform to the curvature of the roll; and where comparatively thick blocks are used, such blocks may advantageously be formed with concave inner faces and convex outer faces, for the same

purpose. In practice, the blocks will be 55 about two inches square, and about three-quarters of an inch in thickness, or they may be circular or oblong; but obviously the particular shape and dimensions may be varied.

By connecting additional rows of blocks 60 to the structure already formed, or by detaching rows therefrom, strips, sheets or forms of any desired size may be produced, so as to enable them to be fitted to rolls of 65 widely different diameters and lengths; it being understood, of course, that the fastening devices of the outside rows, or the edges of the backing strips, are secured together in some suitable way in order to hold the 70 padding on the roll.

In constructing the blocks, they may be 75 cut from sheets of cork of the proper thickness; or layers may be cut from cork sheets and then pasted or otherwise fastened together to form a block of the desired thickness. Also, the blocks may be constructed of ground cork compressed into block form; the same applying equally, of course, to the linoleum, wood pulp, felt, or other construction material employed. The grooves 80 may be formed in the blocks during their actual manufacture, or after their molding or shaping has been completed.

The accompanying drawing shows various embodiments of the invention; and 85 therein:

Figure 1 is a plan view of a portion of a sheet of the improved padding;

Fig. 2 is a view showing one form of 90 metal backing sheet which may be employed;

Figs. 3 and 4 are views of two different blocks which may be used therewith;

Fig. 5 is a view showing another form of 95 backing sheet and its associated block;

Figs. 6 and 7 are views of still other forms;

Fig. 8 is a view showing a textile fabric 98 backing sheet.

Referring more particularly to the drawings, the strip or sheet therein represented 100 consists of a plurality of blocks 1 of the same size and thickness, arranged in longitudinal and transverse rows. In the construction shown in Fig. 1, these blocks are connected together at their adjacent corners by means 105 of wires 2, which fit in surface grooves 3 formed parallel with, and spaced a slight distance from, the marginal edges of the

blocks; said grooves, in consequence, intersecting one another adjacent the corners of the blocks, at which points perforations 5 are formed transversely through the blocks. 5 The connecting wires 2 are passed through the perforations 5 and their ends fastened together in some suitable manner.

The blocks may have flat outer and inner faces, but they may, if made thicker, be 10 given a concavo-convex formation in cross-section, as shown.

The strip or sheet composed of the connected rows of blocks and made of suitable dimensions to fit a standard or other ironing roll, may be applied directly to the roll, but it is preferably mounted on and secured to a backing sheet. This backing sheet may be of metal or of textile fabric, as may be desired; and in the case of the metal backing sheet 7, represented in Figs. 5, 6 and 7, such sheet may be formed with perforations to permit the attachment of the blocks. In Fig. 5, the perforations 8 are relatively large, and the blocks are subjected to pressure to force them through the perforations. In Figs. 6 and 7, the perforations are smaller, and serve to permit the passage of staples 9 therethrough (Fig. 6), or of bolts 10 (Fig. 7), the staples fitting in the grooves 3 formed in the outer faces of the blocks, while the ends of the bolts take into small nuts 11 which are arranged in countersunk recesses 12 in the blocks.

Figs. 2, 3 and 4 show a construction 35 which I consider of importance; such construction embodying an arcuate metal backing sheet 14 formed upon its outer face at suitable intervals with transverse ribs 15. The blocks 16 are adapted to be inserted between the pairs of ribs and to be removed therefrom in the event of injury; and to enable a proper fit to be obtained, the inner or lower longitudinal edges of the blocks are cut away so as to provide recesses or 45 seats 17 conforming to the shape of the ribs, the upper faces of such seats projecting over and resting upon the tops of the ribs. The blocks may, if desired, be faced or lined upon their bottoms with wear plates 18, preferably made in two parts, these plates or 50 plate sections extending into and lining the faces of the seats.

In the construction illustrated in Fig. 8, 55 the backing sheet 19 is of textile fabric, instead of metal. The blocks themselves may

be cemented or otherwise secured to the backing sheet.

In practice, the metal backing sheet may, and preferably will, be made in sections, so that in the event of the blocks of any one section becoming injured, that section may be removed bodily and replaced by a new one loaded with fresh blocks. The sections may be connected together in any desired manner. It is also possible to apply the 65 blocks directly to the rolls in some cases, as the rolls may be perforated or ribbed in the same manner as the backing sheets or holders themselves.

I claim as my invention:

1. Padding for ironing rolls, comprising connected rows of relatively small blocks of fibrous material arranged side by side; and a flexible backing sheet to which said rows are secured, said sheet adapted to conform to the curvature of the ironing roll and to completely encircle the same. 70

2. Padding for ironing rolls, comprising rows of relatively small blocks arranged side by side; and a metallic backing sheet 75 on which said rows are mounted, and to which they are secured, said sheet conforming to the curvature of the ironing roll and adapted to completely encircle the same.

3. Padding for ironing rolls composed of 80 rows of relatively small blocks having the lower part of their sides cut away so that the lower portions will be narrower than the tops, and a metal backing having ribs to securely hold the lower part of the blocks 85 and over which the upper portions of the sides of the blocks project, said backing conforming to the curvature of the ironing roll and adapted to completely encircle the same. 90

4. Padding for ironing rolls composed of 95 relatively small blocks arranged in longitudinal and transverse rows, and having the lower part of their sides cut away so that the lower portions of the blocks will be 100 narrower than the top portions thereof, and metal facing means attached to the lower edges; and a metal backing having ribs between which the blocks slide and are securely held thereby, said backing conforming to the curvature of the ironing roll and adapted to completely encircle the same. 105

In testimony whereof I affix my signature.

AMMIEL F. DECKER.
